UNITED STATES PATENT OFFICE.

CHARLES O. SISLER AND LLOYD D. SMILEY, OF UNIONTOWN, PENNSYLVANIA,

SELECTIVE RINGING AND TALKING DEVICE.

No. 927,816.

Specification of Letters Patent.

Patented July 13, 1909.

Application filed October 2, 1908. Serial No. 455,863.

To all whom it may concern:

Be it known that we, CHARLES O. SISLER and LLOYD D. SMILEY, citizens of the United States, residing at Uniontown, in the county 5 of Fayette and State of Pennsylvania, have invented certain new and useful Improvements in Selective Ringing and Talking Devices, of which the following is a specification.

This invention relates to electrical apparatus and refers especially to a lock-out device for selective communication upon a single pair of wires between parties upon the wires.

An object of this invention is the provision of a device of this character that will enable parties to intercommunicate upon the same wires to the exclusion of all other parties connected upon the same wires and that 20 enables a party upon the wires to communicate with an outside party to the exclusion of all other parties upon the same wires. With this arrangement there will be a saving of a large percentage of wire in the construction of a telephone line.

Another object of this invention is the construction and arrangement of a device of this character that will operate on either the common or on the local battery systems 30 in present use so that it can be adapted to use in large office buildings, private exchanges and the like.

The invention further designs a device of this structure that can take the place of 35 small exchanges in outlying districts by installing the device upon the main switch board of the system.

A still further object of this invention is the provision of the device that can be 40 positioned in a telegraph system to do away with the confusion in signaling operators from the main telegraph stations.

Other objects and advantages will be apparent from the following description and 45 it will be understood that changes in the specific structure shown and described may be made within the scope of the claims without departing from the spirit of the invention.

In the drawings forming a portion of this 50 specification, and in which like numerals of reference indicate similar parts in the several views, Figure 1 is a diagrammatic view of a system of wiring of a telephone circuit 55 having the apparatus applied thereto, Fig. 2 is a front elevation of the device, Fig. 3

is a side elevation of the same, Fig. 4 is a front elevation of the device, having the casing removed, Fig. 5 is a top plan view of the device showing the contact arm in a 60 depressed position, the casing being in section. Fig. 6 is a vertical sectional view of the device looking toward the front thereof, Fig. 7 is a side elevation of the device as applied to a subscriber's telephone instrument.

Referring now to the drawings, 10 designates a base which is adapted to be positioned in the vertical and which is provided with the binding posts 11 and 12 for the connection of the circuit wires to actuate the apparatus. A mounting 13 is positioned upon the outer face of the base 10 which extends outwardly and supports upon its upper face a pair of magnets 14, the wire 15 of 75 which is secured to the binding post 11. The post 11 is connected to the binding post 12 by a wire 16. The opposite wire 18 of the magnets 14 leads to a condenser 59 mounted upon the base 10 adjacent the magnets 14. The opposite lug of the condenser 59 is connected to one of the posts 12 by a wire 19 and to the ring 43 by a wire 20.

Adjacent to the magnets 14 at the edge of the base 10 is positioned a post 21 which 85 carries at its upper end a pivotally mounted armature 22 which swings vertically before the extremities of the magnets 14. The armature 22 is provided with a leaf spring 23 upon its upper face at the pivoted end thereof, which spring is carried backwardly about the extremity of the armature 22 where it is tensionally held in such position by a pin 24. The forward or free end of the armature 22 is provided with a guide 90 25 which is carried by the base 10 and which serves for keeping the armature in the same plane throughout its operations. The extremity of the armature 22 is forked to receive the lower end of a pawl lever 26 which 95 is secured between the forks by a pivot pin 27 and which is guided in its operation by a guide 28 which is raised from the face of the base 10. The guide 28 carries a leaf spring 29 which extends upwardly therefrom and engages the edge of the pawl lever 100 26 for the purpose of tensionally holding the pawl lever 26 in a central position. The armature 22 is provided with a suitable stop 105 30 to prevent the same from rising beyond the rest 25 under the tension of the spring 23.

Intermediately of the upper end of the base 10 a rigid shaft is positioned upon the outer face thereof as shown at 31 which carries a sleeve 32 upon the upper end of which is revolvably mounted a ratchet wheel 33 for engagement with the pawl lever 26. The sleeve 32 also carries a loosely mounted contact arm 34 which is provided upon its outer face with a stud 35 which engages in 10 a recess formed in the under face of the ratchet 33. The arm 34 is pressed into engagement with the ratchet 33 by means of a coil spring 36 which is positioned between the base 10 and the under face of the arm 15 34. The shaft 32 is provided with a nut 37 for the purpose of preventing the displacement of the sleeve 32.

The complete apparatus is provided with a casing 38 which is positioned over and 20 about the same to protect the several parts thereof from dust and undue contact whereby the parts may be broken or displaced. The casing 38 carries an inwardly extended arm 39 which is provided with a locking 25 pawl 40 for engagement with the ratchet to prevent a backward movement of the same.

The base 10 carries a circular ring 43 which is concentrically disposed about the shaft 31 and which is formed of a current 30 conducting substance and which is provided with a plurality of recesses into which contact points are adapted to be inserted.

When the arm 34 is in its normal inoperative position it is engaged against the neutral contact point 41 and held in that position by a thrust rod 42 which is carried by the casing 38 and is operated from the outside thereof, by the receiver hook. As shown in the drawings the ring 43 is provided with a contact point 44 five points around from the neutral contact 41. The ring 43 is provided with one more aperture than the number of subscribers or parties upon the line, as for instance if the line be 40 a party line having ten parties connected thereon the ring 43 will be provided with 11 recesses into which contact points may be inserted. The ratchet 33 is in a like manner provided with eleven teeth to correspond to 45 the eleven apertures or points of contact. The arm 34 is provided upon its outer extremity with a contact 45 which tensionally engages the contact points as the arm is actuated during the operation of the device. 50 The bar 42 is preferably provided with a rubber tip for engagement with the upper face of the arm 34.

In Fig. 1 where the diagram of the wiring is shown the calling circuit follows the 60 course here mentioned: A wire 46 is lead from the ground through a condenser 47 and into a magneto machine 48 where the current is produced. From the magneto the wire 46 leads to a circuit closing key 49 out 65 into the main line passing through the opera-

tors calling plug. The current travels from the main line 46 through the wire 50 to the ring 43, through the contact point 44 where it passes through the arm 34 and out through the wire 51 into the bell magnets 52 of the 70 phone thence through the condenser 53 to the ground. This circuit is closed by the key 49 which is positioned at the central office and which is actuated in the usual manner. The selecting current of the apparatus is produced by a dynamo 54 or the like which preferably produces an alternating current and which is connected to the main line through the wires 55 and 56, the circuit being closed by a key 57. The wire 56 is 80 lead out to the party phones where it is divided into sections 58 which are connected to the binding posts 12 of the lock-out devices which lead through the magnets 14 into the condensers 59 then through the wires 85 19 out onto the main line 46 through the wires 50. The current produced by the source 54 travels through this circuit above mapped out and also passes into the indicator 61 which is positioned at the central 90 station for the purpose of pointing out the exact positions of the arms 34 at the party phone. A condenser 62 is also employed between the wire 55 and the indicator 61.

The indicator 61 is of the same structure 95 as the lock out device which is used at each of the party phones with the exception that the arm 34 is rigidly carried upon the sleeve 32 and strikes a contact point at each aperture which is formed in the ring 43 as all 100 parties are connected through the indicator. The sleeve 32 is extended to the outer face of the casing of the indicator 61 where an indicator hand 65 is positioned to mark off upon a dial 66 the positions of the arms 34 105 upon the lock-device at the party phone.

In Fig. 1 of the drawings the apparatus which is marked off between the dotted lines A, B and C is employed at the central station and serves to control the communications of the separate party phones. 110

The casing 38 is provided with an aperture in the front thereof in which is positioned a piece of glass 67 or the like for the purpose of reading a dial 68 which is positioned upon 115 the outer face of the arm 34 to indicate when the main line is not busy. The glass 67 is positioned directly over the neutral contact point 41 so that the dial can only be read when the arm 34 is in the neutral 120 position.

The operation of the device is as follows: When the line is not in use the arms 34 are all positioned upon the contact points 41 and the dial 68 indicates the same through 125 the glass 67. When central receives a call for number 5 of a party line the selecting key 57 is actuated five times to make and break the circuit which passes from the main lines 46 and 56 through the wires 58, the 130

magnets 14, condenser 59, sections 19 and back to the main lines through the wire 50 causing the magnets 14 to actuate the pawl lever 26 and swing the arm 34 five points.

5 The arm 34 of the party phone which registers to this number is now connected to the point 44 whence the current is passed through the phone 63. It is thus seen that the remaining phones upon a line are dis-

10 connected for the reason that the arms 34 are out of contact with the proper points 41 or 44 and therefore the party in communication with the phone registering to the five points can use the same to the exclusion of

15 the remaining parties. Supposing that there are ten parties on the line and that number 5 desires to call number 8. Number 5 would have to ring central in the usual manner and raise the receiver to release the

20 hook and to depress the thrust rod 42 to force the arm 34 out of engagement with the ratchet 33 so that number 5 can hold the point. Central now closes the magnet circuit eight times and actuates the arms 34 to

25 move eight points with the exception of the arm 34 at the party number 5, as it is disengaged from the ratchet 33. As number 8 is the only party whose contact point 44 is in alinement with the arm 34 the line is

30 open only to the parties number 5 and number 8.

What is claimed is:—

1. In selecting mechanism, a base, magnets disposed upon said base, a ring on said base, a neutral contact point on said ring, a second contact point positioned upon said ring, a shaft centrally disposed of said ring, a sleeve on said shaft, a ratchet rigidly carried at the upper extremity of said sleeve, a head on said shaft for securing said sleeve in position, a loosely mounted arm on said sleeve, a spring about said sleeve for frictionally holding said arm against the under side of said ratchet an armature positioned in juxtaposition to said magnet and a pawl lever carried by said armature for the purpose of engaging and actuating said ratchet.
  2. A selecting mechanism comprising a base, magnets secured upon said base, a post positioned on said base, an armature pivotally mounted upon said post in juxtaposition to said magnets, a stop for limiting the movement of said armature, a rest positioned on said base for supporting said armature, a pawl lever pivotally carried in the outer extremity of said armature, a guide positioned on said base in engagement with said
- lever, a spring disposed on said guide for tensionally holding said lever centrally and mechanism adapted to be actuated by said lever for making a circuit for a phone on a party line.
3. A device of the character described having a ring, contact points on said ring, a shaft mounted centrally in said ring, a sleeve on said shaft, a head on said shaft for preventing the displacement of said sleeve, a ratchet disposed about the upper end of said sleeve having an aperture formed in the under face thereof, an arm loosely mounted upon said sleeve, a spring disposed about said sleeve for tensionally holding said arm against the under side of said ratchet, a stud upon the upper face of said arm for engagement in said aperture at times, a thrust bar for depressing said arm from said ratchet, means for actuating said ratchet and a pawl for engagement with said ratchet for the purpose of preventing the back movement of the same.
4. A selecting mechanism comprising a base, magnets supported upon said base, an armature pivotally supported upon said base in proximity to said magnets, a spring for normally holding said armature away from said magnets mounted upon said base, a rest on said base of said armature, a pawl lever carried in the forked end of said armature, a guide positioned on said base for engagement with said lever a spring disposed on said guide for engagement with said lever, a shaft mounted on said base, a pawl mounted in juxtaposition to said shaft, a ratchet mounted about said shaft for engagement with said pawl an arm loosely mounted on said shaft beneath said ratchet, a spring for tensionally holding said arm against said ratchet, said spring being disposed about said shaft, a stud on said arm for engagement at times in an aperture in said ratchet, a ring concentrically disposed on said base about said shaft, contact points disposed above said ring and a thrust lever for depressing said arm against one of said contact points, said pawl lever adapted to engage and actuate said ratchet for the purpose of actuating said arm.
- In testimony whereof we affix our signatures, in presence of two witnesses.
- CHAS. O. SISLER.
LLOYD D. SMILEY.
